UNITED STATES PATENT OFFICE

2,502,270

ELASTIC FLUID COMPRESSOR OF THE
JET TYPEClare Kenzie Newcombe, Fleet, England, assignor
to Heat Pumps Limited, London, England, a
British companyApplication June 19, 1946, Serial No. 677,886
In Great Britain April 13, 1945

6 Claims. (Cl. 230—95)

1

This invention is for improvements in or relating to elastic fluid compressors of the type (hereinafter referred to as jet compressors of the type described) in which the kinetic energy of a high speed motive fluid jet is used to induce, accelerate and compress a secondary stream of fluid. A single pressure stage of jet compressors of the type described usually comprises a motive fluid or power nozzle, a mixing throat and a diffuser in which the compression of the two streams takes place.

An object of the present invention is to provide an improved jet compressor of the type described having the characteristics of high efficiency, good flexibility, compactness of design and in certain cases ability to operate at extremely high temperatures.

The invention provides a jet compressor of the type in which the kinetic energy of a high speed motive fluid jet is used to induce, accelerate and compress a secondary stream of fluid comprising in combination a plurality of power nozzles for the motive fluid and associated respectively with the power nozzles a plurality of separated induction conduits adapted for entraining streams of the secondary fluid and constituting separate chambers within which said streams of secondary fluid will be intermixed with jets of motive fluid from the associated power nozzles, said induction conduits being arranged as a ring-like series and being so disposed as to impart to the mixture of primary and secondary fluid in each separated conduit a rotational movement about the axis of the aforesaid series.

According to a feature of the invention the induction conduits may be of helical form disposed about the periphery of a member formed as a body of rotation, e. g. cylindrical, conical, hyperboloidal or ellipsoidal.

In one construction the compressor comprises inner and outer shells of frusto-conical form nested one within the other to provide between them an annular gap within which is disposed a series of helical guide vanes spaced apart to constitute between adjacent members of the series a set of induction conduits for the secondary fluid. There may be associated with the leading end of each guide vane a nose-cap arranged to provide a nozzle for the motive fluid, the throat area of the nozzle being adjustable at will.

An example according to the invention will now be described with reference to the accompanying drawings (largely diagrammatic) in which

2

Figure 1 is a perspective view of the compressor, a section being broken away for the sake of illustration.

Figure 2 is a perspective view of a portion of the inner bore of the compressor; and

Figure 3 is an exploded view of one of the guide vanes and the controlling members associated therewith.

Like reference numerals indicate like parts in the three figures. In Figures 1 and 2 certain of the guide vanes have, for clearness of illustration, been omitted.

In this example the compressor comprises an inner shell 20 and an outer shell 21 both of frusto-conical form, the shell 20 being nested within the shell 21 so as to provide between them an annular gap 22 decreasing in depth from the narrow to the broad end of the conical structure. The intake to the compressor is at the narrow end of the structure as a whole, and the discharge at the broad end. The shells 20, 21 are surrounded by a cylindrical casing 23, the space between the outer shell 21 and the casing 23 forming an intake manifold 25 for the primary or motive fluid.

Between the two shells 20, 21 there is provided a series of helical conduits (hereinafter referred to as the mixing conduits) each of rectangular section. Each mixing conduit is formed between adjacent elements of a set of guide vanes 24 extending lengthwise in the gap 22, helically disposed over the outer surface of the inner shell 20 and bounded top and bottom by the shells 21, 20. The vanes 24 are secured in position by screws, by welding or in any other convenient manner. Alternatively, the vanes may be formed integrally with the inner or outer shell.

Motive fluid nozzles are provided at the leading wedge-shaped ends of the guide vanes 24, each nozzle being formed by a nose-cap 26 arranged in front of the leading end of a corresponding guide vane. Each nose-cap 26 is bored out at 27 (see Figure 3), and fitted with a sleeve 28 having ports 29, 30 discharging through rectangular passages 31 to opposite sides respectively of the leading end of the associated guide vane. The flow of motive fluid from the manifold 25 to the sleeve ports 29, 30 is controlled by pistons 32 axially movable within the sleeves. Each piston 32 is formed with a longitudinal fluted passage 33 and circumferential recesses 34 through which the motive fluid has access to the sleeve ports. The pistons 32 are axially movable at will, to increase or decrease the compressor capacity (by increasing or decreasing the effective

area of the port openings) by means of a multi-lobe cam 35 located co-axially within the inner shell 20 and rotatable by any convenient means.

In operation, the motive or primary fluid is supplied through the manifold 25 to the outer ends of the sleeves 28, thence down the fluted passages 33 and through the sleeve ports 29, 30 to the passages 31. Secondary fluid is thereby induced to flow through the mixing conduits between the guide vanes 24 and by virtue of the helical form of the conduits, the mixture of primary and secondary fluid is given a spinning motion. The discharge from the compressor is taken through a duct 40 and exit 41. Passage of the compressed fluid to the duct 40 may be controlled by a diffuser, similar to that employed in centrifugal compressor design, comprising a ring of airfoil type blades 42 (see Figure 2) mounted on the broad end of the inner shell 20 and arranged for boundary layer suction. Motive fluid may be supplied from the manifold 25 to ejector slots formed in the blades 42.

In this example the compressor parts are so designed that (a) the ratio of the height of the entrance throat of each mixing conduit divided by its width is greater than 2.5, and (b) the ratio of the width of each guide vane 24 at the entrance throat divided by the width of the associated nose-cap 26 (also measured at the throat) is between the limits 0.75 and 1.50. Importance is attached to the foregoing features of design.

Various modifications may be made in the construction above described without departing from the essentials of the invention. For example, instead of employing the co-operating sleeves 28 and pistons 32, the motive fluid nozzles may be formed between the internal edges of the feed passages 27 in the nose-caps 26, and the sides of the leading wedge-shaped ends of the associated guide vanes, the nozzle throat areas being adjustable by effecting relative approaching or separating movement between the guide vanes and the nose-caps. Again, instead of helical conduits on a conical surface, the spinning effect on the mixture of primary or motive fluid and secondary fluid may be obtained—as has already been indicated—by suitably directed conduits formed on hyperboloidal, ellipsoidal or equivalent surfaces. The motive fluid nozzles and mixing conduits may be arranged for either radial or axial flow.

I claim:

1. A jet compressor with stationary fluid flow channels and of the type in which the kinetic energy of a high speed motive fluid jet is used to induce, accelerate and compress a secondary stream of fluid comprising in combination a plurality of power nozzles for the motive fluid and associated respectively with the power nozzles a plurality of separated induction conduits adapted for entraining by jet compressor action streams of the secondary fluid and constituting separate stationary chambers within which said streams of secondary fluid will be inter-mixed with jets of motive fluid from the associated power nozzles, said induction conduits being arranged in a ring-like series and being so disposed

as to impart to the mixture of motive and secondary fluid in each separated conduit a rotational movement about the axis of the aforesaid series, without recourse to rotating fluid flow channels.

5 2. A jet compressor according to claim 1 comprising two stationary annular shells separated by a gap within which helical blades in a ring-like series are fixed to define the separated induction conduits aforesaid.

10 3. A jet compressor with stationary fluid flow channels and of the type in which the kinetic energy of a high speed motive fluid jet is used to induce, accelerate and compress a secondary stream of fluid, comprising in combination inner and outer stationary shells of frusto-conical form nested one within the other to provide between them an annular gap, a series of helical guide vanes fixed within said gap and spaced apart to constitute between adjacent members of the series a set of induction conduits for the secondary fluid and a set of power nozzles associated respectively with the entry ends of the induction conduits for directing jets of motive fluid into said conduits.

25 4. A jet compressor of the type in which the kinetic energy of a high speed motive fluid jet is used to induce, accelerate and compress a secondary stream of fluid, comprising in combination inner and outer shells of frusto-conical form nested one within the other to provide between them an annular gap, a series of helical guide vanes disposed within said gap and spaced apart to constitute between adjacent members of the series a set of induction conduits for the secondary fluid and associated with the leading end of each guide vane a nose-cap arranged to provide a nozzle for directing motive fluid into the corresponding induction conduit, the throat area of the nozzle being adjustable at will.

30 40 5. A jet compressor as claimed in claim 4 in which the compressor parts are so designed that (a) the ratio of the height of the entrance throat of each induction conduit divided by its width is greater than 2.5, and (b) the ratio of the width of each guide vane at the entrance throat divided by the width of the associated nose-caps, also measured at the throat, is between the limits 0.75 and 1.50.

45 50 6. A jet compressor according to claim 4 in which each induction conduit is of rectangular cross-section and in which the nozzles aforesaid are mounted to direct jets of motive fluid along opposite side walls of each induction chamber, said walls being constituted by the aforesaid guide vanes.

55 CLARE KENZIE NEWCOMBE.
